R. K. JACK

MANIFOLD FOR INTERNAL COMBUSTION ENGINES

Filed Aug. 11, 1924

Inventor

By his Attorneys *Robert R. Jack*

Blauweorg, Spencer to Flint.

UNITED STATES PATENT OFFICE.

ROBERT K. JACK, OF LANSING, MICHIGAN, ASSIGNOR TO GENERAL MOTORS CORPORATION, OF DETROIT, MICHIGAN, A CORPORATION OF DELAWARE.

MANIFOLD FOR INTERNAL-COMBUSTION ENGINES.

Application filed August 11, 1924. Serial No. 731,459.

My invention relates to internal combustion engines, and particularly to manifold structure designed for use with multiple cylinder engines; the principal object of the features of manifold construction in which my invention consists being to provide for a more effective heating of the combustible mixture as it flows from the carburetor through the intake manifold of the engine, and into the cylinders thereof.

A further object of my invention is to provide a heating arrangement which will be simple in construction, and one which may be readily produced by simple casting operation at present in use; and a still further object of my invention is to provide a manifold structure including heating means for a portion of the intake manifold and wherein the amount of exhaust gas employed for heating purposes may be regulated to produce proper heating of the combustible mixture and a proper operation of the engine.

In the drawing accompanying and forming a part of this specification, and wherein the preferred embodiment of my invention is illustrated:

Figure 1 is a view showing a portion of a multiple cylinder internal combustion engine in side elevation, the same being equipped with my invention;

Figure 2 is a view showing the intake and exhaust manifolds of my invention partly in side elevation, and partly in section upon a plane extending longitudinally of said members;

Figure 3 is a view also showing the intake and exhaust manifolds partly in plan, and partly in section upon a horizontal plane extending along the exhaust manifold;

Figure 4 is a view showing a transverse section upon a plane indicated by the line 4, 4, Figure 1;

Figure 5 is a fragmentary view showing the casing whereby a heating chamber is provided for the intake manifold, as seen from a position above the same, looking down.

Although the drawing accompanying and forming a part of this specification illustrates what I regard as the preferred form of my invention it will be appreciated that the same may be variously modified, and that my invention includes such modifica-

tions of the particular form thereof illustrated as come within the scope of the concluding claims.

Referring now to the drawing, the reference numeral 6 designates a multiple cylinder internal combustion engine which may obviously be of any particular form, as my invention is not limited to use of the manifold construction wherein it consists in connection with any particular multiple cylinder engine.

The intake manifold involved in my invention is made up of or comprises an upright conduit 7 which leads from the carburetor 8, and a plurality of lateral conduits 9 leading from the upper end of said upright conduit to the intake ports of the engine. In the particular manifold structure illustrated three such lateral conduits are employed, two being arranged opposite one another, and the third being arranged at right angles to said opposite conduits, this being because the manifold illustrated is designed for use with a six cylinder internal combustion engine.

Formed integrally with the intake manifold during the manufacture thereof by suitable casting operations is a casing 10 which encloses the confluence or junction between said several conduits, and which casing provides a heating chamber 11 about the upper end of the upright conduit 7 and the inner ends of the lateral conduits 9. This casing is open at its top, as best shown in Figure 5; and the same is provided with vertically disposed internal partitions 12 located one upon each side of the intake conduit 7 and extending downward from the upper end of the casing, and terminating short from the bottom thereof, to thereby provide openings 13 beneath the lower ends of said partitions. The heating chamber within and provided by the casing 10 has no openings leading into or out from the same other than the openings which result from the open top construction referred to and the partitions therein; and the path of exhaust gas therethrough is obviously from the exhaust manifold downward upon one side of the partition 12, through the openings 13, and upward upon the other side of said partitions and back into the exhaust manifold.

The exhaust manifold included in my in-

vention extends alongside and is illustrated as located above the intake manifold, said exhaust manifold having branches 14 leading from the exhaust ports of the engine 5 and through which the exhaust gases enter the manifold. This exhaust manifold is provided with an opening shown at 15 in its under side in the drawing, which opening is of such size, and is so located as to register with the open upper end of the casing 10; so that the heating chamber is placed in communication with the interior of the exhaust manifold through the opening in the latter and through the open upper end 15 of the casing 10. The exhaust and intake manifolds are suitably fastened together at the joint between them by providing said members with flanges which abut against one another, and by the use of suitable bolts 16 20 extending through said flanges, as will be appreciated.

In order to cause exhaust gases from the exhaust manifold to flow through the chamber 11, and to regulate the amount of exhaust gases flowing through said chamber and thus the degree of heating of the combustible mixture flowing through the intake conduit, I provide a valve adjacent the said openings; said valve being shown as an 25 oscillating valve 17 carried by a shaft 18 the ends of which are shown as supported in bearings 19 in the external wall of the exhaust manifold and which valve, when in the position shown in full lines Figures 2 30 and 4, will deflect the exhaust gas and cause it to flow downward and into the heating chamber 11 upon one side of the partitions 12, then through the openings 13 at the lower ends of said partitions, and finally upward 35 upon the opposite sides of said partitions and back into the exhaust manifold; the exhaust gas flowing into and from the heating chamber through the open top of the casing 10 and through the opening 13, as 40 will be understood.

When the controlling valve 17 is in a horizontal position as shown in dotted lines in Figure 2 little if any flow of exhaust gas will occur through the heating chamber, and 45 the heating of the mixture is obviously at a minimum when the valve is in the dotted line position. The valve may, however, be made to assume various positions and, as necessarily follows, the amount of exhaust gas flowing through the heating chamber is dependent upon the position which the said valve is made to assume.

The controlling valve 17 in the embodiment of my invention illustrated is so arranged as to operate in unison with the throttle valve of the carburetor, to thereby control the flow of combustible mixture to the engine and the heating of the same simultaneously. The throttle valve of the carburetor is carried upon a shaft, the position

of which is indicated by the numeral 20, which shaft and throttle valve are operated by a lever carried by the shaft indicated by the numeral 21. The numeral 22 indicates a rod operable from the dash or instrument board of the vehicle with which the engine is commonly used, said rod being connected with one arm of the lever 21 and the other arm thereof being connected with an arm 23 at the end of the shaft 18, through a suitable link 24. The upper end of this link slides freely through an eye 25 carried by the arm 23; and a spring 26 is interposed between the eye and a stop collar 27 upon the rod 24, in order that the throttle valve 17 may be moved after movement of the valve 20 is arrested, as by coming into engagement with a suitable stop at 28, Figure 2.

The interior of the exhaust conduit is illustrated as provided with an internal ledge 29, see Figure 4, which provides a port or opening in which the valve 17 is located. This, however, is a matter of convenience for enabling a close fitting of the valve in the passage which it controls, and a more effective stop of the flow of exhaust gas past the same when the valve is in its upright position shown in Figure 3, to be secured, rather than a necessary and essential detail of the valve in question. As above suggested, the valve 17 is shown as provided with a lip or extension 30 which engages a stop at 28 when the valve is in its down position and, as appears in Figure 4, said valve is provided with a portion 31 extending below the shaft 18 which makes close contact with the upper wall of the intake conduit when the valve is in its vertical position, as shown in Figure 1.

In view of the premises it will be appreciated that the intake and exhaust manifolds are entirely separate and distinct from one another as structures, and are manufactured each independently of the other, thereby much simplifying the making of the same; and that the manifold structure regarded in its entirety is one which can be much more readily cast than is the case wherein similar manifolds are combined in a single integral structure. The two manifolds, while they are commonly assembled before attaching them to the engine, are structurally separate and independent, thus avoiding strains in the manifold structure when the same is in use which is a fault frequently met with in structures wherein similar manifolds are integral with one another. At the same time an extremely effective heating is secured as the heat is applied to the intake manifold by the use of a chamber of large capacity, and which is in direct communication with the exhaust manifold and, finally, that no separate and independent conduit leading exhaust gas away from the heating chamber is necessary as the exhaust

gases employed for heating are returned to the exhaust manifold, and flow therefrom into and through the same exhaust conduit that leads from the exhaust manifold.

5 Having thus described and explained my invention, I claim and desire to secure by Letters Patent:

1. In manifold structure for multiple cylinder internal combustion engines, an intake manifold having an upright conduit leading from a carbureter, and a plurality of lateral conduits leading to intake ports of the engine; a casing enclosing the confluence of said several conduits, and which casing 10 is open at its top and provides a heating chamber about the upper end of said upright conduit and the inner ends of said lateral conduits; an exhaust manifold extending along and located above said intake manifold and having branches leading from exhaust ports of the engine, and an opening in its under side so arranged as to register with the open upper end of the casing aforesaid; and a valve located adjacent said openings and adapted to cause varying amounts of exhaust gas flowing through said exhaust manifold to flow through the open upper end of said casing and into said heating chamber, and out from said heating chamber, and 15 into said exhaust manifold.

2. In manifold structure for multiple cylinder internal combustion engines, an intake manifold having an upright conduit leading from a carbureter, and a plurality of lateral conduits leading to intake ports of the engine; a casing enclosing the confluence of said several conduits, and which casing is open at its top and provides a heating chamber about the upper end of said upright conduit and the inner ends of said lateral conduits; an exhaust manifold extending along and located above said intake manifold and having branches leading from exhaust ports 20 of the engine, and an opening in its under side so arranged as to register with the open upper end of the casing aforesaid; an oscillating shaft supported in bearings provided in the wall of said exhaust manifold, and located substantially in the plane of the opening therein; and a valve carried by said shaft and extending upward and into said manifold, and adapted to cause varying amounts of exhaust gas flowing through said exhaust manifold to flow through the opening in said exhaust manifold and through said heating chamber, and out from said heating chamber through said opening and back into said exhaust manifold.

3. In a manifold structure for multiple

cylinder internal combustion engines, an intake manifold having an upright conduit leading from a carbureter, and a plurality of lateral conduits leading to intake ports of the engine; a casing enclosing the confluence of said several conduits, and which casing is open at its top and provides a heating chamber about the upper end of said upright conduit and the inner ends of said lateral conduits; partitions arranged inside said casing and terminating above the bottom thereof, whereby passages leading from the open top of said casing downward and beneath said partitions, and then upward to the open top thereof, are provided; an exhaust manifold extending along said intake manifold and having branches leading from exhaust ports of the engine, and an opening so arranged as to register with the open upper end of the casing aforesaid; and a valve located above the openings in said exhaust manifold and in said chamber and adapted to cause exhaust gas from said manifold to flow downward through said heating chamber upon one side of said partitions, and upward through said chamber on the other side of said partitions and back into said manifold.

4. In a manifold structure for multiple cylinder internal combustion engines, an intake manifold having an upright conduit leading from a carbureter, and a plurality of lateral conduits leading to intake ports of the engine; a throttle valve adapted to control the flow of combustible mixture through said conduit; a casing enclosing the confluence of said several conduits, and which casing is open at its upper end and provides a heating chamber about the upper end of said upright conduit and the inner ends of said lateral conduits; an exhaust manifold extending along said intake manifold and having branches leading from exhaust ports of the engine, and an opening so arranged as to register with the open upper end of the casing aforesaid; an oscillating valve located adjacent said openings and adapted to cause varying amounts of exhaust gas flowing through said exhaust manifold to flow through said heating chamber; a stop with which said valve engages when in its closed position; a shaft supported in bearings in the wall of said exhaust manifold and whereby said valve is supported, said shaft having an arm at its outer end; a lever whereby said throttle valve may be manually operated; and a yieldable link member intermediate said arm and said lever.

In testimony whereof I affix my signature.

ROBERT K. JACK.
